UNITED STATES PATENT OFFICE

RALPH E. THOMPSON, OF BROOKLINE, MASSACHUSETTS, ASSIGNOR TO GILLETTE SAFETY RAZOR COMPANY, OF BOSTON, MASSACHUSETTS, A CORPORATION OF DELAWARE

METHOD OF MAKING RAZOR BLADES

Application filed November 20, 1930. Serial No. 496,933.

This invention relates to improvements in the art of making and distinguishing thin flexible razor blades having different edge properties.

The extensive use into which safety razors have come in recent years has demonstrated that the same edge properties in blades are not best suited to all users; whereas the edge in a blade of hard temper may exactly meet the requirements of one user, an edge of softer and tougher property will be better suited for the next user, or where a delicate edge formed with a long bevel may fit the requirements of one case, a stouter edge formed with a more obtuse bevel will give greater satisfaction in the next.

In one of its aspects, the present invention consists in improvements in the art of making thin flexible razor blades which will make available for the first time to the public an assortment of interchangeable blades having different edge properties from which the user may make a choice in accordance with his experience, preference or whim. This is a new condition and a new possibility brought about, as already intimated, by the use and manufacture of safety razors and blades on a tremendous scale, and I believe I am the first to recognize this new development in the art and to take steps to satisfy its natural requirements through the medium of the present invention.

The methods of making thin flexible razor blades heretofore practiced involve a series of dependent steps designed to produce in great quantity blades of a single type having uniform edge properties. In another of its aspects, the present invention consists in a series of related steps which are diversified at appropriate points in the method so as to carry variously identified blades to different conclusions in respect to their edge properties. I prefer to modify the construction of each blade blank at the point of departure from the established routine so that it shall mechanically insure the correct selection for the particular series of steps designed for producing its particular edge properties, and at the same time, clearly marked and unmis-

takably distinguished from all other blanks not subjected to or intended to be treated in the same series of steps.

The manner of thus modifying the blank construction and identifying the blanks which is best suited for the requirements of the case consists in end-notching them. The method of my invention, therefore, deals with a series of blanks distinguished from each other by having, for example, three notches, two notches, one notch or no notches formed in one or preferably both ends.

The mechanical function of these notches will be more fully understood and appreciated from the detailed description of the preferred manner of practicing the method of this invention. To illustrate, however, it may be said that at one point in the process the blanks are supplied to a number of grinding machines similar in appearance but so adjusted in range as to impart different angles of bevel to the blanks presented to them respectively. These machines are equipped with magazines so related in their construction to the end notched blanks that only those blanks having the appropriate predetermined arrangement of end notches can be supplied in regular routine. Further, these machines are equipped with automatic feeding mechanism of such character that if a particular blank should be forced into the wrong magazine the feeding mechanism will fail to deliver it to the grinding mechanism, thus automatically selecting or discarding proper and improper blanks. One object of my invention is therefore the provision of a method of so identifying razor blade blanks by notching the ends thereof that each blank after being thus notched can be thereafter treated and finished only in a manner corresponding to the treatment assigned to blanks having that particular identification.

My method of identifying the razor blade blanks not only serves its useful function during the manufacture or treatment of the blanks but also serves to identify the finished blades. The end notches furthermore not only provide a visual and permanent identification for each blade but also provides an identification which may easily be determined

by touch. The provision of the blade thus identified by notches comprises a further object of my invention.

In the accompanying drawings I have specifically illustrated certain applications of my invention but it will be understood that the invention can be otherwise embodied and that the drawings are not to be construed as defining or limiting the scope of the invention, the claims appended hereto being relied upon for that purpose.

Referring to the figures of the drawings:

Fig. 1 is a perspective view of a stack of blade blanks being end notched in accordance with my invention.

Fig. 2 illustrates one of the blade blanks.

Fig. 3 is a fragmentary view of a stacking frame for holding blade blanks during the heat treatment thereof.

Figs. 4, 5 and 6 are fragmentary views of three blades having different cutting edge bevels.

Figs. 7, 8 and 9 are perspective views of three blades with different edge characteristics and identified in accordance with my invention.

Fig. 10 is a perspective view of a magazine adapted to hold only blades end notched in the manner shown in Figs. 4 and 7.

My invention contemplates the manufacture of safety razor blades having different edge characteristics to meet varying requirements and demands, and in accordance with my invention I propose to accomplish this object by an improved method of manufacture. As illustrated and described herein I propose to have four different grades or characters of blades, the distinctions between the blades in these grades being particularly in the cutting edges thereof. The body portion of all the blades will in the normal use of my process be substantially the same, differing only in a manner to visually and mechanically distinguish one from the other as herein-after described. The initial blade blank used in manufacturing these blades will normally be the same regardless of the character of blade to be produced and the initial step of stamping out the blanks is therefore the same for all blanks. Following this step however, the blanks are notched in accordance with the character of blade it is desired to produce and in such manner that they can only pass through the treating machines which will form the blanks into blades having edges corresponding to these desired characteristics.

The first step of my improved process is the forming of the blade blanks 10, one of which is shown in Fig. 2, these blades being commonly stamped out from sheet material. Following this operation certain of the blanks are notched, preferably in the ends thereof in accordance with the character of blade it is desired to produce. In describing my in-

vention herein I have made provision for four different grades or classes of blades, these different classes being hereinafter referred to as classes 1, 2, 3 and 4. The blanks which are to be manufactured into blades of class 1 are not notched, their ends being left intact as in Fig. 2. The blanks which are to form blades of class 2 are provided with a single notch 12 in each end. The blanks which are to form blades of class 3 are provided with two small notches 14 in each end. The blanks are to form blades of class 4 are provided with three notches 16 in each end. It will be noted that the notches 12 are deeper than the corresponding notches 16 and that the notches 14 are spaced differently than are the corresponding notches 16. The purpose of such difference in size and spacing is to assure that each blank will be received only in apparatus or the blank holding magazine thereof which is adapted to give such treatment to the blank as to produce a blade corresponding to the particular class for which it is notched, all of which is hereinafter more particularly described.

Proceeding with the description of my process, the blanks 10 which are to form blades for class 2 are stacked within a holder 18 and secured in place therein by a binding screw 20, the holder being mounted on a grinding machine table 22. This stack of blades is then subjected to the action of a grinding wheel 24 which forms the notches 12 therein. The blanks 10 which are to form blades of classes 3 and 4 are treated in like manner but with grinding wheels to form notches 14 and 16 of the shape, size and location illustrated in Figs. 5, 6, 8 and 9. The blades are thereafter treated through the usual steps of hardening, drawing, grinding, honing and stropping to form the same into finished blades.

In accordance with my process certain apparatus are provided for handling each class of blade. If the preliminary treatment or treatments of certain blade blanks of different classes are to be the same the apparatus therefor will be constructed to take blades of these different classes. Whenever and wherever in the process the treatment of blanks of different classes vary however, the blade handling apparatus are so constructed that they will take only those blanks which have been notched in a corresponding manner. The handling of these blanks requires holders or magazines for holding the blades in stacks and in accordance with my invention these holders or magazines are constructed to receive only those blanks which are to be given a corresponding treatment.

After the blanks are appropriately notched as illustrated in Fig. 1, they are hardened and drawn to the proper degree and for this treatment the blanks are supported in stack formation in a holder such as shown in Fig. 3. This

holder comprises a bottom plate 30, a top plate 32, a plurality of connecting bolts 34, separators 36 and a lifting stud 38. Ordinarily all the blanks will receive the same hardening and drawing treatment and in such case the blank holders for these treatments will be so constructed as to hold all blanks regardless of the end-notching thereof. If however, the differently notched blanks are to receive different heat treatments the holders therefor will be so constructed that the blanks will be received only in those holders in which they will receive the corresponding and proper treatment. For example, the holder shown in Fig. 3 is constructed to receive only those blanks provided with a single notch 12 in their ends. Other holders may in like manner be provided for receiving only those blanks corresponding to the other blade grades or classes.

Following the heat treatment the blades are sharpened, honed and stropped. The machines for performing these operations are provided with blade magazines whereon the blanks are held in stacked formation and from which the blanks are taken individually as treated. One of these magazines which I have illustrated in Fig. 10 comprises a base 40, two relatively spaced pins 42 for engaging through the two outer apertures in the blanks and two further spaced studs 44 for engaging within the end notches 12. This magazine is adapted to receive only those blades which are end-notched at 12 as shown in Figs. 4 and 7 and will reject unnotched blades and blades notched as shown in Figs. 5, 6, 8 and 9. The sharpening, honing and stropping machines are constructed and adjusted to treat and form the blank edges in accordance with the different variations required in the different classes or grades of blades and the mounting of appropriate magazines on these varying machines mechanically and positively assures that only the proper blanks can be received and treated thereon. In accordance with my method of operation it is therefore impossible to make any error in treating the blanks through the various steps of their manufacture into blades.

In Figs. 4, 5 and 6 I have, for example, shown three blades of different edge bevel. The blade 50 of class 2 is provided with an obtuse bevel 52; the blade 54 of class 3 is provided with a sharper bevel 56; and the blade 58 of class 4 is provided with a still sharper and longer bevel 60. These different bevels are formed on different grinding machines in which the grinding tools are differently adjusted to produce such bevels. The machines for producing the bevel 50 are provided with magazines like that shown in Fig. 10 which will receive only blanks of class 2. The machines for producing blanks 54 and 58 are in like manner provided with maga-

zines which will respectively receive only blanks of classes 3 and 4. It is therefore impossible to grind blanks of each class in a machine other than one of the machines which is arranged to give the blank the bevel corresponding to its particular class.

Likewise, in honing and stropping the blades, it may be desirable to produce a class of blades wherein the edge is rather coarse, a class wherein the edge is relatively fine, and a class with an intermediate edge. The three blades shown in Figs. 7, 8 and 9 have their edges drawn in a greatly exaggerated manner to illustrate three such classes. The blade 70 of class 2 is provided with relatively coarse edges 72, the blade 74 with intermediate edges 76, and the blade 78 with fine edges 80. These blades are end-notched at 12, 14 and 16 and the honing and stropping machines for producing the different edges 72, 76 and 80 are provided with magazines adapted to receive only blades correspondingly notched as shown in these figures. It will therefore be seen that the use of my method precludes and makes error in the production of different grades or classes of blade impossible.

I claim:

1. That improvement in the art of making safety razor blades having different edge properties, which consists in producing a quantity of blade blanks, variously notching portions of certain of the blanks to identify the blanks and conform them to fit only certain blade handling apparatus and thereafter treating the different notched blades with a different combination of steps by mechanically handling them in apparatus adapted only to take blades of a predetermined notched form.

2. That improvement in the art of making safety razor blades having different edge properties, which consists in producing a quantity of blade blanks, variously notching end portions of certain of the blanks to identify the blanks and conform them to fit only certain blade holding apparatus and thereafter treating the differently notched blades with a different combination of steps by mechanically handling them in apparatus adapted only to take blades of a predetermined notched form.

3. That improvement in the art of making safety razor blades having different edge properties, which consists in dieing out from sheet stock a plurality of identical blade blanks, hardening and drawing to the same degree all of said blanks, end-notching certain only of the blanks, presenting all of the blanks to two differently adjusted grinding machines each having magazines designed to receive one kind of blank only, whereby the blanks are mechanically selected and ground to different edge bevels according as the blanks are notched or unnotched.

4. That improvement in the art of mak-

- ing safety razor blades having different edge properties, which consists in hardening and drawing a plurality of identical blade blanks, end-notching certain only of the blanks, presenting all of the blanks to differently adjusted grinding machines having magazines with end guides correlating the blanks according to their notches with the adjustment of the machine.
- 10 5. That improvement in the art of making safety razor blades, which consists in producing a quantity of identical blanks, then performing the steps of hardening, drawing, grinding, honing and stropping said blanks, 15 variously notching certain of the blanks at an intermediate point in such series of steps, and modifying each successive step performed on those blanks to produce different microscopic edge properties in the blanks so notched as compared with the blanks unnotched or notched in another manner.
- 20

Signed at Boston, Massachusetts, this 17th day of November, 1930.
